[57] CLAIM

The ornamental design for a training aid unit for a bicycle,
as shown and described.

DESCRIPTION

FIG. 1 is a front view of the training aid unit for a bicycle
showing my new design;

FIG. 2 is a side view of the training aid unit for a bicycle
showing my new design;

FIG. 3 is a back view of the training aid unit for a bicycle
showing my new design;

FIG. 4 is a bottom view of the training aid unit for a bicycle
showing my new design; and,

FIG. 5 is a top view of the training aid unit for a bicycle
showing my new design.

The nature and environmental use of the claimed design
includes attachment to a bicycle seat and frame.
